DESIGN FOR A DISPLAY BOX

Benjamin S. Katz, Cincinnati, Ohio, assignor to
The Gruen Watch Company, Cincinnati, Ohio,
a corporation of Ohio

Application November 19, 1936, Serial No. 66,027

Term of patent 7 years

To all whom it may concern:

Be it known that I, Benjamin S. Katz, a citizen of the United States, residing at Cincinnati, in the county of Hamilton and State of Ohio, have invented a new, original, and ornamental Design for a Display Box, of which the following is a specification, reference being had to the accompanying drawing, forming a part thereof.

In the drawing:

The parts not stippled and not scored have a dull satin finish with the appearance approximately that of velvet.

I claim:

The ornamental design for a display box substantially as shown and described.

BENJ. S. KATZ.
